Wm H. Lewis
Improvement in designs
for spoon and fork handles

Patented May 3, 1859, Fig. 1

Fig. 2

Wm H. Lewis

Nathaniel W. French, witness

P. D. Carpenter

Des. 1098

Wm H. Lewis, of Glastenbury, Conn.
Letters Patent No. 1198. Dated May 3d. 1859.

The schedule referred to in these Letters Patent and making part of the same.

To all, whom it may concern:

Be it known, That I William H. Lewis of Glastenbury, -
County of Hartford and State of Connecticut, have invented or produced a new and
original design to be stamped on the handle of Spoon, Fork, and other articles -
made of Silver, German Silver and other metals, and I do hereby declare that the
following is a full and exact description of the same:

Having reference to the accompanying drawings

Figs 1 and 2

2

Des. 1098

The design represents a Grapewine Foliage upon and around the edge of the handle, as shown in figures 1 and 2. of the accompanying drawings, which I propose to stamp upon both sides of the spoon, fork, or other handle as may be desirable clearly showing the configuration of a grape vine, clusters of grapes, and leaves thereby producing a rich and handsome finish.

I claim the configuration of a Grapewine foliage upon both sides of a spoon fork or other handle, as shown in fig: 1 and 2. of the accompanying drawings.

Witnesses.

Nathaniel W. French.

Is'l. T. Carpenter.

Wm H. Lewis. (Seal)
